PRETZEL

Howard Reisman, Philadelphia, Pa., assignor to J. Reisman & Sons, Inc., Pennsauken, N.J., a corporation of Pennsylvania

Continuation of design application Ser. No. 81,171, Aug. 5, 1964. This application Nov. 30, 1965, Ser. No. 371

Term of patent 14 years

(Cl. D1—13)

FIG. 1 is a front elevational view of a pretzel showing my new design;

FIG. 2 is a side elevational view thereof;

FIG. 3 is a cross-sectional view taken through FIG. 1 along the line 3—3;

FIG. 4 is a cross-sectional view taken through FIG. 1 along the line 4—4;

FIG. 5 is a cross-sectional view taken through FIG. 1 along the line 5—5; and

FIG. 6 is a front elevational view of another embodiment of the pretzel shown in FIG. 1 wherein the openings thereof are of slightly different configuration.

The pretzel shown in FIG. 6 has side and cross-sectional views similar to FIGS. 2—5.

The essential feature of my new design resides in the illustrated central area, of a form of pretzel with its portions flatly aligned and non-overlapping, having a hole therein as shown in FIGS. 1 and 6.

This application is a continuation of my copending application for design patent, S.N. D. 81,171, filed Aug. 5, 1964, and which is now abandoned.

I claim:

The ornamental design for a pretzel, as shown and described.
